UNITED STATES PATENT OFFICE.

HARRY E. KITTLE, OF SYRACUSE, NEW YORK.

TOY.

Application filed September 27, 1924. Serial No. 740,223.

This invention relates to toys and more particularly to toys for amusement and exercise.

The primary object of this invention resides in the provision of a toy constructed to afford amusement and exercise to grown people as well as children.

Another object of this invention resides in the provision of a toy requiring skill to manipulate it.

A still further object of this invention resides in the provision of a toy of such construction that certain motions of the body of an individual, supported thereon, will cause it to progress over the ground.

In addition to the aforesaid objects, this invention resides in providing a toy which will support an individual and convey him as long as he can maintain his equilibrium thereon.

Aside from the foregoing objects this invention resides in the provision of a toy of such construction that its progress can be regulated without affecting its mode of operation.

Since this invention affords amusement and exercise commensurate with the skill of the individual manipulating the same, an appreciable degree of attraction thereto is created and, therefore, another of the objects of the invention is to utilize the same as an advertising medium.

With these and other objects in view, this invention resides in certain novel features of construction, arrangement and combination of elements to be hereinafter set forth in the specification, illustrated in the accompanying drawings and pointed out in the appended claims and, while the disclosure depicts my present conception of the invention, it is to be understood that the right is reserved to resort to such departures from the disclosure as come within the scope of the claims.

In the accompanying drawings forming a part of this application:

Fig. 1 is a perspective view of one form of my invention;

Fig. 2 is a sectional view thereof approximately on line 2—2 of Fig. 1;

Fig. 3 is a similar view on line 3—3 of Fig. 1;

Fig. 4 is a perspective view of another form of my invention;

Fig. 5 is a sectional view approximately 55 on line 5—5 of Fig. 4; and

Fig. 6 is a front view thereof showing an advertising panel carried thereby.

In the present embodiment of this invention, the numeral 5 designates an elongated 60 handle adjacent the lower end of which is pivotally secured a pair of adjustable legs 6. Secured to the handle 5 adjacent the pivotal points of the legs 6 is a loop-shaped bracket 7 constructed not only to form a 65 support upon which the individual must stand to manipulate the toy, but is adapted to form guideways for the legs to maintain their rigidity through the instrumentality of locking pins 8, which secure the legs in 70 adjusted relation on opposite sides of the axis of the handle.

To manipulate a toy of this construction an individual is required to maintain his equilibrium upon the bracket 7 while grasping the handle 5 and, upon succeeding in this particular, movements of the body from side to side, together with certain periods of relaxation of pressure on opposite sides of the bracket, will cause the legs 6 to alter- 80 nately swing in advance of one another. To regulate the strides of the legs 6, they are disposed accordingly in spaced relation to the axis of the handle and secured in their ad- justed positions by the stay-bolts 8. 85

In the form of this invention illustrated in Figs. 4 to 6 the legs 6' are non-adjustable, preferably formed integrally with the handle 5 and support a substantially loop-shaped bracket 7' having its terminals 10 embracing 90 the legs.

In order to utilize this invention as an advertising medium, a panel P having advertising manuscript thereon is fastened thereto in any suitable manner and in any appropriate or convenient position thereon. 95

With this invention fully set forth, it is manifest that a toy adapted to afford amusement and exercise is produced and, through the requirement of skill to manipulate it, attraction thereto will be induced. 100

Having thus described my invention, what I claim and desire to protect by Letters Patent is:

1. A toy of the character described comprising a handle, legs pivoted thereto at points remote from the lower end of the handle, a bracket secured to the lower por-

tion of the handle and extending laterally beyond the sides of the legs, and fastening elements securing the legs to the bracket.

2. A toy of the character described, a handle comprising diverging legs pivotally secured on opposite sides of the handle remote from its lower end, a loop-shaped bracket secured to the handle adjacent its lower end and extending laterally therefrom at substantially right angles thereto, and fastening elements securing the legs to the bracket at points inward of its extremities.

3. A toy of the character described comprising a handle, a loop-shaped bracket secured to the lower end thereof in substantially right angular relation thereto, legs secured to the handle at points remote from the bracket and having their free portions projecting through the bracket inwardly of

its extremities, and fastening elements securing the legs to the bracket at selected points inward of the ends of the bracket.

4. A toy of the character described comprising a handle, a loop-shaped bracket adjacent its lower end, legs carried by the handle and extending through the bracket and securing elements connecting the bracket and legs to the handle.

5. A toy of the character described comprising a handle having legs secured adjacent the lower end thereof and diverging therefrom, a bracket in right angular relation to the handle and extending on opposite sides thereof in the region of the legs, and means securing the legs to the bracket inwardly of its extremities.

In testimony whereof I affix my signature.

HARRY E. KITTLE.
